UNITED STATES PATENT OFFICE.

LAWRENCE E. ROBINSON, OF COFFEYVILLE, KANSAS.

PACKER FOR OIL, GAS, AND WATER WELLS.

No. 927,874.

Specification of Letters Patent.

Patented July 13, 1909.

Application filed April 11, 1908. Serial No. 426,546.

To all whom it may concern:

Be it known that I, LAWRENCE E. ROBINSON, a citizen of the United States, residing at Coffeyville, in the county of Montgomery, and State of Kansas, have invented new and useful Improvements in Packers for Oil, Gas, and Water Wells, of which the following is a specification.

This invention relates to a packer device 10 for use in oil, gas and water wells, and has for its object the provision of means for facilitating the packing of the walls of a well.

Another object of the invention is the provision of a peculiarly constructed, flexible sleeve that is reinforced, and which sleeve is mounted upon a frame that is capable of being lengthened or shortened for the purpose of facilitating the packing operation by 20 the compressing and expanding or stretching of the sleeve.

A further object of the invention is the provision of means for straightening a yieldable or rubber sleeve after it has been compressed, and also to facilitate the removal of the sleeve from the well after it has been drawn to its original position, thus avoiding the usual difficulty of removing a packer, as is experienced when the rubber remains 30 in a collapsed condition.

With these and other objects in view, the invention consists of certain constructions, combinations, and arrangements of parts, as will be hereinafter fully described and 35 claimed.

In the drawings: Figure 1 is a view, in side elevation, partly shown in section, of a device constructed in accordance with the present invention. Fig. 2 is a view, in side 40 elevation, shown partly in longitudinal section, and showing the sections of a frame telescoped and the reinforced rubber or yieldable sleeve compressed. Fig. 3 is a horizontal, sectional view taken on line 3, 3, Fig. 2.

Referring to the drawings 1 designates the internally-threaded annular members or collars which constitute a holding device for receiving the end-links of the chain 7, hereinafter described. The annular members 1 45 are threaded upon threaded-portions formed upon the outer face of the telescoping end

sections 2 and 3 of the metallic frame, constituting a cylinder or casing. Each portion of the frame is provided with a reduced wedge or end-section 4 which is threaded, at its inner end, into the end of the telescoping section, 3, and its outer end is externally threaded for receiving a coupler 6. The sections 2 and 3 may be secured against sliding movement, one upon the other, by means of the threaded structure 5, which threaded structure comprises threads, substantially square in cross section, upon the inner ends of said sections so that, through the medium of a pipe or tube 60 connected to the upper coupler 6, the upper section 3 can be rotated for either unscrewing the same, or screwing the same upon the lower section 2; attached to the lower coupler 6 is, preferably, an anchor, of any 65 suitable structure, which is adapted to have a portion extend into the coupler, and the anchor will hold the packer-device at any desired distance from the bottom of the well, the distance depending upon the length 70 of the anchor. The anchor attached to the coupler 6 will also hold the lower section 2 of the packer-device against rotary movement, which will permit the operator to rotate the upper section 3 for threading the 75 same upon the lower section, when it is desired to either adjust the telescoping sections to their normal position, Fig. 1, or to loosen the upper section, so that the upper section can be reciprocated upon the lower section 80 for causing the flexible sleeve 9 to be compressed or lengthened, resulting in the sleeve, when compressed, engaging the walls 10 of the well.

The sleeve 9 is, preferably, formed from 90 rubber, and the chains 7, constituting reinforcing, flexible, metallic means, are, preferably, embedded in the rubber, and vulcanized therein, and the end-links 6 are fastened, in any suitable manner, to the annular members or collars 6, as hereinafter stated. Therefore, it will be noted that, by forcing the upper section 3 downward, through the medium of any suitable connecting means fastened to the upper collar 95 6, the rubber sleeve 9 will be compressed between the end-collars 6, and causing said 100

sleeve to expand and engage the walls of the well, or, upon drawing upward upon the section 3, the rubber sleeve 9 will be stretched, consequently, removing the sections of the device to their normal position, which will relieve the pressure or strain upon the rubber sleeve, and when removing the device from the hole or well, the sediment can easily pass between the outer face 10 of the rubber sleeve 9 and collars 6 and the sides of the well.

Upon referring to Fig. 2, it will be seen that this view illustrates the packer device when the well is packed, having the chain-reinforced rubber sleeve compressed to the wall; this operation is accomplished after the packer is lowered in the well by means of the tubing attached to the upper coupler, as stated before, and the anchor, or tubing, 20 or other suitable means attached to the lower coupler, is in engagement with the bottom of the well; the anchor not only properly spaces the packer from the bottom of the well, but also offers or produces a 25 resistance by means of which the square threaded connection, for fastening the telescoping sections together, is released or unscrewed by making several turns upon the upper section of the frame or casing.

30 When removing the device from the well, it will be obvious that the upward strain (caused by means of the power connection with the tubing of the upper coupler 6, the chain members 7, running longitudinally of 35 the yieldable or rubber sleeve,) straightens up and draws the flexible sleeve back to its original position, as when first placed into the well, and thus allows a free removal of the packer from the well, permitting the 40 sediments to pass the same freely, as herein-before stated.

From the foregoing description, it will be obvious that I have provided a hollow packer device which comprises a sectional 45 frame, which sections telescope, one upon the other, and mounted upon the frame is a peculiarly constructed yieldable sleeve or casing; the frame or casing provided with means at its ends for permitting the yieldable or rubber, reinforced sleeve to be compressed or lengthened at the will of the 50 operator.

It is to be noted that the beveled, annular portion 2^a constitutes a wedged-structure, 55 which, when one section is slid upon the other section, assists in forcing the rubber sleeve, or yieldable filling means, outward against the wall 10 of the well.

I have found from practical experience 60 that the lower portion 2 is held rigidly by resting on the bottom of the well, whereas portion 3 is movable. At that point where portions 2 and 3 pass through the collars, in

which the chains are embedded, said portions are loosely threaded for a considerable 65 greater distance than the junction of members 2 and 3. About two turns is sufficient to disengage portions 2 and 3, but where portions 2 and 3 pass through the collars, the threading allows for numerous turns. At 70 the junction of portions 2 and 3, the threading is large, and there is approximately one turn to an inch; where portions 2 and 3 pass through the collars, the threading is twelve 75 to the inch. Therefore, the distance in threading would require twelve turns of the upper portion to one at the junction referred to.

The different parts of the packer are assembled as follows, when being manufactured: The lower section 2 of the packer is slid upon 80 the upper section 3 by means of having the lower portion 4 detachable from the lower end of the section 2 and it will be obvious that section 2 can be easily slid over the top of section 3. After sections 2 and 3 have 85 been assembled, the lower section 4 is threaded upon the internal threaded-portion upon the lower end of section 2. The annular members 1, in which are cast or molded links 90 6 of the chain 7, are threaded upon the external threaded-portion of the sections 2 and 3, as shown in Fig. 2, and to facilitate the mounting of said annular members upon the sections 2 and 3, the sections will be in 95 a position similar to that shown in Fig. 2, so as to allow the different sections to easily turn upon each other and prevent the twisting of the chain 7, while the annular members are being threaded upon one of the sections. After all of the sections have been 100 assembled, the packer is then coated with rubber, and thereby embedding the chain 7 and forming a yieldable sleeve as hereinbefore described. It will be obvious that when the packer is assembled, as previously described, the sections 2 and 3 can easily slide upon each other and the threaded structure 105 5 can engage each other and hold the packer in an extended position as shown in Fig. 1.

What I claim is:

1. A device of the character described, comprising a rubber packer sleeve provided with a chain embedded therein, and means connected to the ends of said chain for compressing, and lengthening said sleeve after 115 the same has been compressed.

2. As a new article of manufacture, a rubber packer sleeve provided with a chain embedded therein, and the chain extending, at its ends, beyond the ends of said packer 120 sleeve.

3. A device of the character described, comprising a frame formed of sections, one adapted to slide upon the other, a rubber packer sleeve provided with a chain embedded therein mounted upon said frame, 125

and annular members positioned upon the sections of said frame and having the ends of the chain secured to the annular members.

4. A device of the character described, comprising a frame formed of an inner and an outer section, collars upon said sections, a yieldable packer carried by the frame between said collars, and chains in said packer

and having links at their ends, extending beyond the ends of the packer and secured 10 in the collars.

LAWRENCE E. ROBINSON.
